(57) **CLAIM**

The ornamental design for a ballistic applique insert, as shown and described.

DESCRIPTION

FIG. 1 is a front perspective view of a ballistic applique insert showing our new design;

FIG. 2 is a rear perspective view of the ballistic applique insert shown in FIG. 1;

FIG. 3 is a front elevational view of the ballistic applique insert shown in FIG. 1;

FIG. 4 is a rear elevational view of the ballistic applique insert shown in FIG. 1;

FIG. 5 is a left-side elevational view of the ballistic applique insert shown in FIG. 1;

FIG. 6 is a right-side elevational view of the ballistic applique insert shown in FIG. 1;

FIG. 7 is a top plan view of the ballistic applique insert shown in FIG. 1; and,

FIG. 8 is a bottom plan view of the ballistic applique insert shown in FIG. 1.

The broken lines are directed to environment and are for illustrative purposes only; the broken lines form no part of the claimed design.

1 Claim, 5 Drawing Sheets
